CLAIM

The ornamental design for a marker light bezel, as shown and described.

DESCRIPTION

FIG. 1 is a front, left, top perspective view of a marker light bezel showing our new design;

FIG. 2 is a front view thereof;

FIG. 3 is a rear view thereof;

FIG. 4 is a top view thereof;

FIG. 5 is a bottom view thereof;

FIG. 6 is a left side view thereof, shown in enlarged scale; and,

FIG. 7 is a right side view thereof.

A second embodiment of the claimed design for the marker light bezel is a mirror image of the marker light bezel as shown in FIGS. 1 to 7.
